UNITED STATES PATENT OFFICE.

WALTER M. OLIVER, OF PARSONS, KANSAS.

PACKAGE TIE.

Application filed May 26, 1923. Serial No. 641,659.

To all whom it may concern:

Be it known that I, WALTER M. OLIVER, a citizen of the United States, residing at Parsons, in the county of Labette and State 5 of Kansas, have invented certain new and useful Improvements in a Package Tie, of which the following is a specification.

The present invention relates to a package tie and has for its principal object to 10 provide means for holding the ends of a string which are disposed about a package so that these ends will be prevented from accidental displacement and when desired may be easily detached from the device so 15 that the package may be opened.

Another important object of the invention is to provide a device of this nature having a simple and efficient structure, one which is reliable in operation, inexpensive to manu- 20 facture, durable, attractive in appearance, and well adapted to the purpose for which it is designed.

With the above and numerous other ob- 25 jects in view as will appear as the description progresses, the invention resides in cer- tain novel features of construction, and in the combination and arrangement of parts as will be hereinafter more fully described and claimed.

30 In the drawing—

Figure 1 is a perspective view of a pack- age showing my device thereon,

Figure 2 is a top plan thereof showing a portion of the package tie removed,

Figure 3 is a transverse section through the device, and

Figure 4 is a transverse section through a modified form of the device.

Referring to the drawing in detail it will 40 be seen that 1 designates a package about which the cord 2 is disposed for holding the package together. Ordinarily the ends of the cord 2 would be tied together which is rather a difficult procedure if it is de- 45 sired to have the cord taut. My package tie includes a flat plate 3, a rivet 4, and a dished or concavo-convex plate 5. The plates 3 and 5 are preferably in the form of disks and the plate 5 is smaller in diameter than the plate 3. The convex face of the plate 5 is disposed adjacent the plate 3. A rim flange 6 is formed on the plate 3 extending over the side thereof adjacent the plate 5. The rivet 4 passes centrally through the

plates 3 and 5 and is preferably rigid to 55 the plate 3 while the plate 5 may move thereon toward or away from the plate 3. As is shown in Figure 2 one end of the board 2 is permanently attached to the rivet 4 be- 60 tween the plates 3 and 5. The cord is then 65 passed around the package as may be de- sired for holding the same secure and is then wrapped about the rivet and will be frictionally engaged between the plates 3 and 5. Since it engages the convex face 65 of the plate 5 there will be a wedging ac- 70 tion so that the cord will be prevented from becoming accidentally displaced and yet may be easily disengaged from the package tie when so desired. By having the plate 5 75 movable on the rivet 4 it will be seen that this tie may be used with cords of various thicknesses.

The modified form of the invention shown in Figure 4 includes the plate 3, the rivet 75 4 which is formed integral with the plate 3 and has rigidly disposed thereon the plate 5. The plate 3 of the modified form differs slightly from the plate 3 of the preferred form in that the flange rim 6 is disposed 80 on the side opposite the plate 5.

I have, in the present instance, shown and 85 described preferred embodiments of my in- vention which will give in practice satis- 90 factory and reliable results, and it is to be understood that the same are susceptible of modification in various particulars with- out departing from the spirit or scope of the invention or sacrificing any of its ad- vantages.

Having thus described my invention what I claim as new is:—

A package tie of the class described in- 95 cluding a flat plate provided with a rim flange bent over on one face thereof, a rivet 100 passing through the flat plate and rigidly engaged therewith, and a dished plate on the rivet movable toward and away from the flat plate and having its convexed side adjacent the face of the flat plate over which extends the flange.

In testimony whereof I affix my signature in presence of two witnesses.

WALTER M. OLIVER.
